UNITED STATES PATENT OFFICE.

JOHN M. HANSEN, OF PITTSBURG, PENNSYLVANIA, ASSIGNOR TO FORGED STEEL WHEEL COMPANY, OF PITTSBURG, PENNSYLVANIA, A CORPORATION OF PENNSYLVANIA.

APPARATUS FOR FORGING WHEEL-BLANKS.

No. 866,021.

Specification of Letters Patent.

Patented Sept. 17, 1907.

Application filed May 19, 1906. Serial No. 317,734.

To all whom it may concern:

Be it known that I, JOHN M. HANSEN, a resident of Pittsburgh, in the county of Allegheny and State of Pennsylvania, have invented a new and useful Improvement in Apparatus for Forging Wheel-Blanks; and I do hereby declare the following to be a full, clear, and exact description thereof.

My invention relates to dies for the manufacture of forged steel car or other wheels, its object being to provide means for forging blanks which can by subsequent forging operations be transformed into finished wheels, and in so doing to so operate upon the metal as to produce the wheel with little or no scrap, condense the metal and force the metal displaced in forming the web into the hub cavity of the dies to aid in forming the hub portion of the wheel. The dies are adapted for the practice of part of the method set forth in an application filed by me of even date here-with, Serial No. 317,733.

20 The apparatus comprises, generally stated, the combination of a female or bowl-shaped die having a hub forming cavity, and a male die so constructed as to engage with the blank near the outer edge of the web forming portion of the female die and force it inwardly toward the hub, as well as other operative means working to develop the blank, as hereinafter more particularly set forth and claimed.

In the accompanying drawings Figure 1 is a vertical section of a pair of dies embodying the invention showing the position of the blank before it is operated upon; Fig. 2 is a like view showing the position of the blank when the dies are partially closed; Fig. 3 shows the dies closed; Fig. 4 shows the operation of partially piercing and forming the hub; and Fig. 5 shows the 35 completion of the forming of the hub portion of the blank.

The different dies and other parts of the apparatus are intended to be connected to a powerful press such as a hydraulic press having the different movements necessary for their operation and for the development 40 of the blank. It is not considered necessary to illustrate the different die actuating mechanisms. I will describe the apparatus in connection with the operation of the same upon the blank in its different steps 45 of formation so that their purpose may appear clear.

A suitable blank 1 is raised to a proper forging heat and is placed upon the bottom die 2 which is a male die having a bowl-shaped cavity 3, and preferably having at the upper edge a series of steps 4 for centering the blank upon the die.

As shown in the drawing the cavity 3 of the bowl-shaped die preferably has its upper portion 5 formed substantially vertical, below which there is the inclined web forming portion 6 which, as shown, is con-

nected to the upper portion 5 by means of a curved 55 convex face 7.

Below the web forming portion 6 and connected therewith by a like curve is the central hub forming cavity 8, and leading down from the same is the vertical opening 9 to receive the round end punch 10 or 60 sharp piercing mandrel 11, which are the preferred means for operating upon the hub portion of the blank.

Above the die 2 is the male die 12 which is of smaller diameter than the mouth or upper portion of the bowl-shaped cavity 3 of the lower die so that when it 65 fits therein there is left the rim forming cavity 13.

The lower portion of the die 12 has the annular curved projection 14 preferably having the form shown, and within the same is the hub forming cavity 15, the die also having a central opening 16 for the passage of 70 the punch 17 which co-operates with the punch 10 as hereafter stated. The web forming portion 6 of the lower die and the annular projection 14 of the upper die are so formed that when engaging the metal blank it forces the metal inwardly toward the hub, and in 75 final position preferably brings the web portion 18 of the blank to substantially finished thickness, the metal displaced flowing inwardly to aid in developing the hub.

The manner in which the annular projection 14 of 80 the male die engages with the blank is shown in Fig. 2, first bending the blank into substantially bowl-form, contacting with the blank as it presses it down with its outer curved face 21 and bringing the blank first into contact with the annular convex face 7 of the lower die 85 so that as it binds the blank at that point but little of the metal is forced into the rim cavity 13, the mass of the metal in forming the web being forced to flow inwardly into the hub cavity between the two dies such as that formed by the central cavities 8 and 15, this being well shown in Fig. 3. At the same time the tread or rim forming portion 19 is turned upwardly and the blank is brought into concavo-convex form, preferably 90 substantially into bowl-form as shown.

It will be noticed that the web forming portion of the dies is connected to the rim forming portion thereof, by a gradual curve. This is desirable because it is the point of greatest bend in forming the concavo-convex blank from the flat slab, and by thinning the metal at this point and providing for the gradual curving thereof, liability to cracking of the outer portion of the metal is overcome.

While I prefer to develop the hub by the particular punches and mandrel illustrated in the drawing, it is evident that any suitable means for developing the 105 hub upon the blank formed by the remainder of the dies can be employed.

After the top die 12 is brought down to place, in order

to further develop the hub the central punching dies 10 and 17 are advanced, operating on the metal as it is confined within the hub cavities of the dies so that it cannot spread into the web portions thereof, and therefore 5 by cause the metal to flow longitudinally around the punches upwardly and downwardly, and nearly fill the hub forming cavities 8 and 15, as shown in Fig. 4. The ends 23 and 24 of the punches 10 and 17, which are rounded as shown, act to spread the metal in this way, 10 the punches nearly meeting within the body of the blank, leaving a thin central web 22. While the blank is so confined within the dies the punch 10 is lowered out of the central opening 9 and the piercing mandrel 11 is substituted therefor. The upper punch 17 is 15 raised or set free to be raised and the piercing mandrel 11 is forced upwardly through the blank, as shown in Fig. 5, so piercing the blank and spreading the metal to substantially fill the hub forming cavities 8 and 15 and in this way complete the formation of the blank.

20 In the above operations it will be seen that I am enabled to forge from a flat slab a blank having an annular upturned rim or tread forming portion 19 adapted for subsequent forging into the rim or tread of the wheel; also to bring the web portions 18 to substantially finished thickness, and in so doing utilize the metal displaced by forcing it inwardly to aid in forming the hub, substantially all the metal so displaced being utilized in developing the hub because of the first engagement of the dies with the blank near the 25 outer edge of the web forming portion thereof; and also to utilize all the metal so obtained from the web forming portion and all the metal in the central part of the original blank for developing the hub, spreading it upwardly and downwardly so as to substantially fill the hub cavity, and finally spreading the remainder of the metal in such way as to complete the formation of the hub.

What I claim is:

1. In apparatus for forging wheel blanks, the combination of two forging dies having a hub forming cavity between them, and web forming faces, the web forming faces of said dies approaching most closely near the outer

portion of the web and thereby acting to force the metal of said web portion inwardly into the hub cavity.

2. In apparatus for forging wheel blanks, the combination of a male die and a female die having a hub forming cavity between them, said dies having curved inclined faces adapted to coöperate with each other near the outer edge of the web forming portion of the blank and force the metal inwardly into the hub cavity. 45

3. In apparatus for forging wheel blanks, the combination of a female of bowl-shaped die, a male die adapted to enter within the same and of smaller diameter than the cavity of the female die, said dies having a hub forming cavity between them, and said dies having curved web forming faces approaching most closely at the outer portion of the web forming cavity and thereby acting to force the metal inwardly into the hub cavity. 50

4. In apparatus for forging wheel blanks, the combination of a female die, and a male die of less diameter than the female die, each die having a central hub forming cavity, and said dies having web forming faces approaching most closely at the outer portion of the web forming cavity and thereby acting to force the metal inwardly into the hub cavity. 60

5. In apparatus for forming wheel blanks, a female die having at its upper edge a series of blank centering seats on different levels in combination with a male die adapted to enter the female die. 65

6. In apparatus for forging car wheels, the combination of dies having web forming faces approaching most closely near the outer portion of the web and a central hub forming cavity between them, each die having a central opening communicating with the hub cavity, a pair of co-operating indenting punches fitting in said central opening 70 of said dies and mounted to advance after the closing of the dies and thereby punch the hub portion of the blank 75 and spread the metal within the hub cavity.

7. In apparatus for forging wheel blanks, the combination of a bowl-shaped female die having the upper portion of its cavity provided with vertical walls and its bottom being concavo-convex on radial lines, and a male die of smaller diameter than the female die arranged to enter said female die and having an annular web reducing face coöperating with the convex portion of the bottom 80 of the female die, the space between said dies forming an annular rim cavity and said dies having a centrally arranged hub forming cavity. 85

In testimony whereof, I the said JOHN M. HANSEN have hereunto set my hand.

JOHN M. HANSEN.
